UNITED STATES PATENT OFFICE.

SAMUEL MAZUR, OF BUFFALO, NEW YORK, ASSIGNOR TO THE SESSIONS CLOCK COMPANY, OF FORESTVILLE, CONNECTICUT, A CORPORATION OF CONNECTICUT.

CLOCK.

Application filed December 31, 1924. Serial No. 759,204.

This invention relates to a clock and more particularly a clock having a striking mechanism whereby chimes are sounded for indicating the hour of the day. One of the objects 5 of this invention is to provide a clock of this character having a better musical tone; another object is to so construct the frame that the same is stronger and permits the main springs to be taken out of the clock and replaced when required without dismantling 10 the striking and escapement mechanisms and re-adjusting the same; and also to reduce the cost of manufacture and permit of putting out an inexpensive clock having the qualities 15 equal to those marketed heretofore of higher grade.

In the accompanying drawings:

Figure 1, is a rear elevation, partly in section, of a clock mechanism embodying my 20 improvements.

Figure 2, is an edge view of the striking wheel.

Figure 3, is a front elevation of the same.

Figure 4, is a side view partly in section of 25 the clock mechanism containing my invention.

Figure 5, is a perspective view of part of the hammer operating mechanism.

Figure 6, is a similar view of part of the 30 trip mechanism which controls the operation of the striking mechanism.

Figure 7, is a similar view of the locking mechanism associated with the striking mechanism.

Figure 8, is a rear elevation of the main frame of the clock.

Figure 9, is a side view of the same, partly dismantled.

Figure 10, is a rear elevation of the lower 40 section of the rear plate detached from the companion upper section of the same.

Figure 11 is an end view of the standard and associated parts of the sounding device. Figure 12 is a vertical section taken on line 45 12—12 Fig. 1.

Similar characters of reference indicate like parts in the several figures of the drawings.

As is well known a striking clock consists 50 generally of a time mechanism and a striking mechanism which are mounted side by side as substantially distinct units in the main frame, the time mechanism in the present example being arranged mainly in the right 55 hand part of the main frame when viewed

from the front and the striking mechanism mainly in the left hand part of the same.

The main frame of the clock comprises a front upright plate 11, which is preferably constructed from a single piece or sheet of metal, a rear plate consisting of an upper section 12 and a lower section 13 having its upper end overlapping the lower end of the upper section, upper posts 14 detachably connected at their front and rear ends by screw 60 nuts 15 with the upper end of the front plate and the upper end of the upper section of the rear plate, lower posts 16 detachably connected at their front and rear ends by screw nuts 17 with the lower end of the front frame plate and the lower end of the lower section of the rear frame plate, and bolts 18 detachably connecting the overlapping ends of the sections of the rear frame plate.

The center shaft 19 carrying the usual hour hand of the clock is pivotally mounted in suitable bearings on the central part of the front frame plate and the lower part of the upper section of the rear frame plate.

In the lower right hand part of the main 75 frame is arranged the spring motor for operating the time mechanism which motor comprises a time motor axle or shaft 20, a time motor spring 21, and a main driving gear wheel 22. This time shaft is journaled at its front end 80 in a bearing on the front frame plate and the lower section of the rear frame plate. The main time spring 21 is secured at its opposite ends to the main time shaft or axle and the lower rear frame section, and the main 85 gear wheel 22 is secured to the main time shaft 20. Motion is transmitted from the main time gear wheel 22 to the central hour shaft by a train of gearing represented generally by the numeral 23 in Fig. 1, and having the axles or shafts of its gear wheel journaled in suitable bearings on the front frame plate and the upper section of the rear frame plate.

Above the center shaft 19 is arranged the 100 axle or shaft 24 forming part of the strike trip or controlling mechanism, this shaft being also journaled at its front and rear ends in suitable bearings on the upper part of the front frame plate and the upper part of the 105 upper section of the rear frame plate, as shown in Figs. 1 and 4. Adjacent to the shaft 24 is arranged the shaft 25 forming part of the locking mechanism which last mentioned shaft is also journaled at its front 110

and rear ends in suitable bearings in the upper part of the front frame plate and the upper part of the upper section of the rear frame plate.

5 Within the upper left hand part of the main frame is arranged the striking wheel or disk 26 which is mounted on a striking shaft or axle 27 journaled at its front and rear ends in bearings arranged on the front frame plate and the upper section of the rear frame plate.

10 Adjacent to the striking wheel is arranged the locking wheel 28 which is mounted on an axle or shaft 29 journaled in bearings on the front frame plate and the upper section of the rear frame plate.

15 In the lower left hand part of the main frame is arranged the spring motor for operating the striking mechanism, which motor comprises a striking motor shaft or axle 30, a striking spring 31, and a driving gear wheel 32. The striking motor shaft is journaled at its front and rear ends in bearings on the front frame plate and the lower section of the lower section of the rear frame plate.

20 The main striking spring is secured at its opposite ends to the main shaft 30 of the striking motor and to the lower section of the rear frame plate and the main striking gear wheel 32 is operatively connected with the motor shaft 30, in any approved manner. Motion is transmitted from the driving wheel of the striking motor to the axle 29 of the locking wheel, and the axle 27 of the striking wheel, by any suitable or well known means 25 such as the train of gearing represented generally in Figs. 1 and 4 by the numeral 33.

Heretofore the front and rear plates of the main frame were each made of a single piece of metal which is objectionable because this necessitated taking off the entire rear plate in order to render the main springs of the striking or time mechanism accessible for repairing. Such removal of the rear frame plate disturbed all the bearings of the important parts of the clock such as the striking mechanism and the escapement mechanism and these had to be carefully re-adjusted after the rear frame plate was replaced which involved undue loss of time and expense.

30 By making the rear plate of the frame in sections it is possible to mount the main parts of the clock which do not often get out of order, such as the escapement and striking mechanisms on one section of the rear frame plate, and the spring motors comprising the main springs and their axles or shafts on another section of the rear frame plate. This renders it possible to detach the rear frame plate section which carries the spring motors from the companion rear frame section for effecting repairs of these motors and then replacing the same without disturbing the bearings of any other parts of the clock mechanism. It follows from this that re-adjustment 35 of the parts of the clock other than the motors

is therefore not required, thereby enabling replacement of the main springs to be effected expeditiously and economically.

Furthermore, by making the rear frame plate in sections and overlapping those ends 70 of the same which are detachably connected with each other, the main frame is re-inforced and materially strengthened due to the double thickness of metal at the joints between the frame plate sections so that the 75 same is not liable to be sprung out of shape and disengage its bearings from the shafts or axles which are journaled therein. The frames of clocks as heretofore constructed, were usually so weak that the same would get 80 out of shape by the jarring to which they were subjected during transportation and this made it frequently necessary for a retail dealer to repair and re-adjust a clock having sprung frame plates and displaced bearings before the time piece was in condition for selling to the trade. The present construction prevents such springing of the main frame and the loss incident to repairing the 85 same.

90 In the preferred form of the connection between the upper and lower sections of the rear frame plate the coupling bolts 18 adjacent to the springs 21, 31 of the motors of the time mechanism and striking mechanism are so placed that when these springs expand upon unwinding they will strike these bolts so that the final expansion of these springs will be directly outwardly and away from the central part of the clock mechanism and thereby avoid interfering with the latter.

95 An additional advantage in making the rear frame plate in two sections is that smaller dies can be employed which not only reduces the cost because they can be made to fit easier, but they can also be operated with less power.

100 The trip shaft or axle 24 as usual is provided with a trip lever or arm 34 which is adapted to be engaged and shifted by an hour tappet 35 on the center shaft 19, a stop arm 36 mounted on the trip shaft 24 and adapted to be engaged by the stop pins 37 on the locking wheel for effecting a preliminary stop in the rotation of the same, and a raising arm 38 arranged on the trip shaft and adapted to be raised simultaneously with the stop arm 36.

105 Unwinding of the strike motor spring 31 is controlled by a counting wheel 39 mounted on the strike motor axle 30 so as to be operatively connected with the inner end of the main striking spring 31 and a counting arm 40 connected with the shaft 25 of the locking mechanism and having a hook 41 adapted to be engaged successively with counting notches 42 arranged in an annular row on the periphery of the counting wheel. This counting arm is disengaged from the counting wheel whenever the strike tappet 35 115

BEST AVAILABLE COPY

shifts the trip arm 34 at which time the raising arm 38 engages the underside of the counting arm and lifts the same so that its hook 41 is disengaged from the respective notch 42 of the counting wheel and permits the latter to turn under the action of the main striking spring 31. 5

As the stop arm 36 descends and moves out of the path of the stop pins 37 of the locking wheel 28 the counting arm drops with its hook into engagement with the next following counting notch 42 and holds the counting wheel against further rotation, thereafter the stop pin 37 is engaged by the hook 43 of a locking lever or arm 44 which is secured to the locking shaft 25 so as to turn therewith, thereby holding the locking wheel against rotation and arresting the parts associated therewith. 10

Between the arms 40 and 44 the shaft 25 of the locking mechanism is provided with a controlling arm or lever 45 which has a hook 46 adapted to engage successively with shoulders 47 formed on diametrical sides of the periphery of the striking wheel or disk 26, for arresting the rotation of the latter. Whenever the striking wheel is released and turned the same operates the mechanism for sounding the chimes and this in its preferred 15 form is constructed as follows:—

On a suitable support such as the bottom 48 of the enclosing casing of the clock below the clock mechanism is arranged a metal chime or bell stand which in the present instance 20 consists of a base 49 secured to the bottom 48 by a screw 50 and a standard 51 rising from this base. From the upper part of this standard projects one or more chime or bell rods 52 of different tones which are adapted 25 to be struck by a hammer mechanism and thus audibly announce the time of the day. In order to provide a solid and substantial support for these chime rods the standard is made from a comparatively large mass of 30 metal. However, to permit the chime rods to vibrate more freely when struck a slot or notch 53 is formed on the rear side of the standard between its upper and lower ends and opening in a direction opposite to the 35 front side of the standard from which the chime rods project.

This forms a comparatively slender connection between the upper and lower parts of the standard and causes the chime rods to 40 produce a greater volume of tone than otherwise would be the case.

Although the chime rods may be mounted on the chime stand in various ways it is preferable to mount the same in the following 45 manner:—

In the upper part of the standard the same is provided with a plurality of mounting openings, one for each chime rod, there being two of the latter in the present instance of different length and tone. Each of these 50 mounting openings extends through the standard from its front side to its rear side and consists of a rear part 54 which is cylindrical and a front part 55 which is conical and flares from the cylindrical part forwardly to the front side of the standard. Each chime rod is preferably constructed of metal which is round in cross section and the same 55 comprises a front body 56, a rear shank 57, and an intermediate neck 58 connecting the body and shank. The body is comparatively long and forms the main part of the chime rod. The shank is comparatively short and is secured in the cylindrical part of the mounting opening in the stand. The neck 60 of the chime rod is of conical form and tapers rearwardly from the body of the rod to the shank thereof. At the rear small end of the neck the same is joined with the front end of the shank by an abrupt shoulder 59. 65

By thus making the front part 55 of flaring or trumpet shape the sound of the chime rod is spread over the clock case and thus increases the volume of the same. By constructing the junction of the reduced neck 60 of the chime rod with the relatively large shank of the same by an abrupt or square shoulder the vibrating capacity of the rod is increased resulting in greater resonance of the rod when the same is struck by a hammer. 70

Each of the chime rods is adapted to be struck adjacent to its fixed end by a hammer mechanism having a hammer head 60 of metal and a facing 61 of leather on said head which is adapted to hit the chime rod and thus vibrate the same and causing the rod to sound. Each of these hammer heads is mounted on the lower arm 62 of a hammer lever, the rear arm 63 of which is adapted to be engaged by an actuating mechanism whereby this lever is turned in the direction for raising the hammer and then let go so that the hammer will descend solely by gravity and strike the respective chime rod without the aid of 75 springs. By this means the hammer mechanism is materially simplified and the cost of manufacturing reduced. Each hammer lever is preferably made integrally from a single piece of metal wire and the same is mounted between its lower and upper arms on a hub 64 having a central opening 65 which receives a horizontal pivot pin 66 and thus forms the axis about which the hammer lever turns. This hammer lever may be secured to its hub in any suitable manner but preferably by placing this lever in a notch 67 in one side of the respective hub and then securing the lever in this notch either by soldering or closing or pinching the metal of the hub 80 against opposite sides of the hammer so that the latter is held in the hub by friction. The hubs of both hammer levers are preferably mounted on the same pivot pin 66 and the latter is mounted on a hanger 68 depending from the lower part of the lower section of the 85

rear frame plate. The movement of the hammer levers in the direction for engaging the facings of the hammer heads with the chime rods is preferably limited by a buffer 59 which normally arrests each hammer lever in a position in which its hammer head is out of contact with the respective chime rod, as shown in Fig. 1, but which permits the hammer lever to spring sufficiently to engage its 10 hammer head with the chime rod and then rebound out of engagement therefrom. This buffer is preferably secured to the lower part of the hanger 68 in position to be engaged by the upper arm of the respective 15 hammer lever. The arm of each hammer lever is preferably arranged normally in a horizontal position or nearly so while the upper arm thereof is bent upwardly into angular form and terminates in the space adjacent to the opposing parts of the time mechanism and striking mechanism motor springs. The motion for actuating the hammer lever is derived from the striking wheel or disk 26 and is transmitted from the same to the 20 hammer lever by two intermediate levers. One of these intermediate levers comprises a hub 70 having an upper arm 71 adapted to be engaged successively by tappets or pins 72 on diametrically opposite sides of the front 25 face of the striking wheel or disk 26 and a lower arm 73 having a laterally projecting finger 74 engaging with the upper arm 63 of one of the hammer levers. The other intermediate lever consists of a hub 75 having an upper arm 76 adapted to be engaged successively by tappets or pins 77 arranged on diametrically opposite sides of the rear face of the striking wheel or disk 26, and a lower arm 78 provided with a laterally projecting finger 79 for engaging with the upper arm 68 30 of the other hammer lever. The hubs 70, 75 of the two intermediate levers are pivotally mounted at their front and rear ends on the front frame plate and the upper section of the rear frame plate. As the striking disk rotates the tappets on opposite faces thereof deflect the upper arms of the intermediate levers which stand in the path of these tappets and thereby cause the hammer levers to 35 be turned in the direction for raising the hammers from the chime rods and when the tappets clear the intermediate levers the latter are returned to the starting position by the return movement of the hammer levers, 40 the front arms of which descends under the weight of the hammer heads thereon. 45 The relative arrangement of the two sets of striking tappets on opposite faces of the striking wheel is such that two corresponding tappets on opposite faces of this wheel form a pair and operate their respective hammers one after another so that two strokes, one on one chime rod following closely after a stroke on the other chime rod will be given 50 for each hour unit. For example at one o'clock a stroke will be delivered against both chime rods but one after the other; at two o'clock two pairs of strokes will be given, the strokes of each pair following each other closely and a longer interval of rest occurring 55 between successive pairs of strokes and so on for each further hour of the day. 60 If desired one of the chime rods may be sounded by a single blow to indicate the half-hour interval of time. This is accomplished 65 in the present case by providing the center shaft 19 with an auxiliary or half-hour striking tappet 80 diametrically opposite the main or hourly striking tappet 35, which auxiliary tappet is adapted to engage with an auxiliary 70 upper intermediate arm 81 on the upper side of the hub 70 and raise the hammer head of the rear chime rod for producing a single stroke of the respective rod every half-hour. From the foregoing it will now be clear that 75 the striking mechanism will give two taps of the chime rods for each hour unit and a single tap on one of the chime rods half way between the successive hour units. 80 This clock not only has fewer parts than 85 clocks of this general character as heretofore constructed, but it also is much stronger and not liable to be put out of order by severe 90 blows during shipment from the factory to the dealer or customer and its main springs 95 can be quickly repaired at small cost owing to the ease with which the same can be removed and replaced without taking out other important parts of the clock which would require re-adjustment and loss of time. 100 Furthermore the striking mechanism is of 105 simpler, less expensive and more durable construction, and the chime rods are so mounted that tones of greater volume are produced. 110 For the purpose of limiting the return movement of the intermediate levers the hub of each of these levers is provided with a stop arm 82 which is adapted to engage an adjacent part of the main frame, as shown in 115 Figs. 1 and 4. 120 Although the chime or bell rods may be constructed of various metals which may answer the purpose more or less satisfactorily it is preferable to make them of an alloy having the following constituents in substantially the proportions given:—

	Per cent.
Copper	60.16
Nickel	11.88
Lead	0.04
Zinc	27.83

The above total 99.91% and the balance of 0.09% is represented in waste especially in the zinc which is not taken into account. 125

By making the chime rods of the herein-described alloy a quality of tone is produced upon striking the rods which is much sweeter and more agreeable than those heretofore known. 130

I claim as my invention:—

1. A clock comprising two chime rods, two hammer levers each provided with a head adapted to strike one of said rods, two intermediate levers each adapted to actuate one of said hammer levers, and a striking wheel provided with striking pins on its opposite sides, the pins on each side being adapted to actuate one of said intermediate levers, said hammer levers and intermediate levers turning about different axes. 25
2. A clock comprising two chime rods, means for striking said rods successively for each unit hour comprising two hammer levers having hammer heads adapted to engage said rods successively, two intermediate levers engaging said hammer levers, a striking wheel having a plurality of pairs of striking tappets adapted to engage said intermediate levers, a center shaft having a tappet, and an auxiliary arm connected with one of said intermediate levers and adapted to be engaged by said tappet, said hammer lever and intermediate levers turning about different axes. 30
3. A clock comprising a frame, and a striking mechanism including a hammer lever pivoted on the frame, an intermediate lever pivoted on the frame and adapted to engage said hammer lever and having a stop arm adapted to engage said frame, and a striking wheel having a tappet adapted to engage said intermediate lever, said hammer lever and intermediate lever turning about different axes. 35
4. A clock comprising a sounding member, means for sounding said member comprising a hammer head adapted to engage said member, a main hammer lever carrying said head, an intermediate member engaging said hammer lever, and a striking wheel provided with tappets for engaging said intermediate lever. 40

SAMUEL MAZUR.
